ELECTRIC FUSE

Leland L. Parker, Spokane, Wash.

Application January 27, 1948, Serial No. 4,607

4 Claims. (Cl. 102—70.2)

(Granted under the act of March 3, 1883, as
amended April 30, 1928; 370 O. G. 757)

1

The invention described herein may be manufactured and used by or for the Government for governmental purposes without the payment to me of any royalty thereon.

My invention relates to safety arming mechanisms for fuzes and particularly to an arming mechanism for electrically actuated bomb fuzes, said arming mechanism having a time delay mechanism adapted to control the time of arming of said fuze. More specifically my invention relates to means for utilizing a variable-force driving source such as a wind vane to provide the driving force for driving an escapement mechanism to provide a definite controllable time delay for a fuze mechanism.

My invention is applicable to any projectile fuze of the mechanical or electrical type for which safe operation requires that the projectile remain in the unarmed condition until a predetermined interval after it is released but the invention is particularly applicable to electrically actuated bomb fuzes in which an electric squib is fired to set off the fuze, and my invention will be disclosed in connection with such a fuze although it will be understood that it is equally applicable to any other type of fuze employing a wind vane or turbine.

So-called "air travel" arming has long been used for projectile fuzes. In this type of device a wind vane or turbine is so associated with the arming device that after a predetermined number of turns of the wind vane due to travel of the projectile through the air, the fuze is in the armed condition. One important objection to this type of arming is that the time required to complete the arming depends on the velocity of the projectile during the arming, and this is different for different sizes and types of projectiles such as bombs and rockets. As it is desirable to use one type of fuze for more than one type or size of projectile, it will be seen that the arming time is not necessarily a definite quantity when air travel type of arming is employed. The arming time with this type of device will also vary with the horizontal initial speed of the projectile, which is undesirable. It has therefore been proposed to use a spring driven clock mechanism, and such mechanisms have been developed but they lack the essential safety of air travel mechanisms in that they may operate if accidentally started even when the projectile is not in flight.

Driving a clock mechanism directly from a wind vane shaft does not always supply a sufficiently uniform torque to the clock mechanism since the wind vane speed may vary widely so that it is difficult to obtain the desired accuracy of timing; moreover the direction operation of slow speed clock work from a high speed shaft through gearing results in large forces on the clock mecha-

nism which makes it difficult to secure good operation.

It is an object of my invention to secure accurate "time" arming (as against "air travel" arming) by the use of a clock work timing mechanism driven from the high speed turbine shaft, the above mentioned and other difficulties being obviated by the use of a slipping or a non-rigid connection between the turbine and the timer. This connection consists of a magnetic torque transmitting device between the driving shaft and the constant speed clock work so constructed that if the shaft speed exceeds that of the driven initial clock work element there will be slippage between the two. It is also an object to provide a novel means combining a wind vane driven generator and a magnetic torque transmitting device so that practically no extra space or material is used over that normally used by the generator so that in the case of an electric fuze of known type (for example a proximity fuze) which normally employs such a generator, the mechanical power source for a "time" arming mechanism is obtained at little or no cost in space or weight.

Other objects are to provide a fuze arming mechanism that can be used with existing types of fuze; and that is reliable and fool-proof in operation.

Other objects and advantages will be apparent from the following description and drawings in which:

Figure 1 is a longitudinal cross-sectional view of a projectile embodying my invention, in the unarmed state,

Figure 2 is an enlarged sectional view similar to Figure 1 of the clock work mechanism, shown in the armed position,

Figure 3 is a sectional view taken on line 3—3 of Figure 1,

Figure 4 is a sectional view taken on line 4—4 of Figure 1,

Figure 5 is a sectional view taken on line 5—5 of Figure 1 showing the rotor in the unarmed position.

In the drawings reference numeral 1 represents the forward end of a projectile such as a bomb, rocket, etc., having a fuze 2 in the nose thereof. This fuze is provided with a wind-vane or turbine 3 for driving a shaft 4 which passes through a chamber 5 which houses the operative elements of the fuze.

My invention is particularly applicable to electric fuzes requiring electric power, such as proximity fuzes although it is not limited to any particular type of fuze, and the electric components and other working elements of the fuze may be housed in chamber 5. Shaft 4 rotates in bearings 4a and 4b and has fastened at its free end rotor 6 which is a strongly permanently mag-

netized rotor of highly retentive material such as for example that known in the trade "Alnico," so magnetized as to provide a number of alternate north and south poles. The rotor 6 is surrounded by a number of salient projecting paramagnetic stator members 7 and 8 alternately disposed as shown in Figures 1 and 4 of which members 7 are associated with one end of winding 9, and members 8 are associated with the other end of winding 9, the two ends being joined by a paramagnetic spool or core member 10. It will be seen that rotation of rotor 6 produces a rotating magnetic field which sweeps past stator members 7 and 8 to induce an alternating E. M. F. in stator winding member 9 which thus serves as a generator. The ends of coil 9 are connected by leads 11 and 12 respectively, to slip rings 13 and 14, respectively, mounted on casing 15. This casing is firmly fastened to the stator and to tubular casing sleeve 21 so that these elements all move as a unit, with shaft 4 and rotor 6 free to rotate with respect to this unit which in turn is free to rotate in bearings 18 and 19, while conducting current to the fuze circuit (to be later described) through stationary brushes 16 or 17 in contact with slip rings 13 and 14 respectively.

Fastened to sleeve 21 for rotation therewith is gear 22, which drives the clock work generally indicated by numeral 23 in Figure 1. Gear 24 of this clock work is fastened to escapement wheel 25 which drives pallet 26 to form an escapement for limiting the speed of the clock work system. The assembly of gear 24 and wheel 25 is itself internally threaded to cooperate with the threaded portion of a rod 28 as shown in Figures 1 and 2. In the initial position of the arming mechanism rod 28 extends into a hole 32 in rotor 33, passing through supporting member 31. Rod 28 is keyed to member 31 by a key 29 so that it can freely slide longitudinally with respect to 31, but can not rotate with respect thereto. Rotation of gear 24 is therefore effective to withdraw rod 28 from rotor 33. This rotor carries a squib 34 having external contacts 35 mounted on the rotor and is urged toward rotation by spiral spring 37 but restrained by rod 28. When the rod is withdrawn from hole 32 spring 37 rotates the rotor 33 180° into the armed position where it is aligned with booster lead 44 and where contacts 35 engage stator contacts 41 so that the squib 34 is in circuit through leads 32 with the generator and the electric fuze elements in chamber 4. Rotor 33 is stopped in this position by pin 38 moving in arcuate slot 39 until it is stopped by member 31 from further rotation.

The operation of the system shown should now be apparent. Arming wire 46 is pulled when the projectile is released. The shaft 4 immediately begins to rotate as the projectile moves through the air driving rotor 6 at high speed and generating an E. M. F. in winding 9. This produces also a reaction torque on the stator and hence on casing 15 which tends to drive the casing in the same direction (but at a slower speed). This motion is transmitted by casing gear 22 to clock work gear 24 to drive the clock work and at the same time to withdraw the rod 28 from the initial safe position shown in Figure 1 into the final position shown in Figure 2, when the rod is out of engagement with rotor 33, enabling the latter to rotate from the safe position into the armed position. Subsequent closing of the squib circuit by the electric fuze elements in chamber 5 can now detonate the squib to explode the pro-

jectile. The time required to release the rotor for rotation is determined by the constants of the clock work and the physical parameters of the system and is fixed in the system shown; but it will be obvious that time regulating means may be incorporated if desired so that the time will be varied as required. This may also accomplish by varying the length of rod 28 which is engaged with rotor 33 or by using a standard clock escapement movement with a spring loaded balance wheel and varying the spring loading, or in any desired known manner.

It will be seen that the above described construction accomplishes the objects of the invention but it will be apparent that other mechanical motions and elements than the ones shown could be used to accomplish the same objects within the scope of the invention as shown in the appended claims.

I claim:

1. In combination, a fluid driven turbine, a shaft driven thereby, a substantially constant speed rotating system driven by said shaft, and a slipping connection between said shaft and said system, said slipping connection comprising a magnetic coupling, said magnetic coupling comprising a generator having a rotating field member driven by said shaft and an armature member free to rotate about the same axis of rotation as said field member and mechanically coupled to said constant speed rotating system.

2. An arming system for an electric fuze comprising a wind vane in the nose of said fuze, a shaft driven by said wind vane, a clockwork timer driven by said shaft, a slipping connection between said timer and said shaft, a powder train interrupter actuated to arming position by said clockwork, a latch for retaining said interrupter initially in said safe position, spring means biasing said interrupter into armed position and means actuated by said timer for releasing said latch from said retaining position after a predetermined time of operation of said timer, said slipping connection being a magnetic coupling device and including a generator having a rotating field member driven by said shaft and an armature free to rotate about the same axis of rotation as said field member and mechanically coupled to said clockwork timer.

3. The invention recited in claim 2 and including sliprings on said armature member, leads from the armature winding to said sliprings, and stationary external brushes bearing on said sliprings.

4. The invention recited in claim 2 and including a squib on said powder train interrupter, squib contacts on said interrupter, and circuit connections including said generator, said squib and said electric fuze.
